UNITED STATES PATENT OFFICE.

RICHARD E. LEWIS, OF CHICAGO, ILLINOIS.

HANDLE FOR FLOOR-SURFACING MACHINES.

Application filed September 28, 1925. Serial No. 58,988.

There is a type of motor-driven floor sanding machine in which the front end is supported on a cylindrical roller covered with sand paper or the like and rotating rapidly in the direction tending to move the machine ahead; the rear end of the machine being supported on suitable wheels; and there being a handle projecting rearwardly for the purpose of moving or controlling the movements of the machine. When the machine is operating on a floor the handle is used to hold it back that is, to restrain it from moving ahead as fast as it will go; and the handle is also used to control the downward pressure on the roller, the pressure being varied by pushing upwardly or downwardly on the rear end of the handle. It is comparatively easy and convenient to pull back on the handle, but to push up on the same in order to increase the pressure of the roller, is very tiresome.

The object of the present invention is to produce a simple and novel construction whereby the mere act of holding back or pulling on the handle of a machine of the character briefly explained above will produce a downward pressure on the surfacing roller; so that the operator need only concern himself with pulling on the handle in order to control the machine both as to speed of travel and degree of pressure.

The various features of novelty whereby my invention is characterized will hereinafter be pointed out with particularity in the claims; but, for a full understanding of my invention and of its objects and advantages, reference may be had to the following detailed description taken in connection with the accompanying drawing, which is a side perspective view of a machine to which my invention is applied; the handle being shown in full lines in its normal position and in dotted lines in the position which it occupies when the machine is in operation and a rearward pull is exerted on the handle.

Referring to the drawing, 1 represents the body of a floor surfacing machine supported at the front end by a cylindrical abrading roller 2 that is adapted to rotate rapidly in the clockwise direction, as viewed in the drawing. The rear end of the machine is mounted on wheels 3 or other suitable supporting elements. The motor for driving the roller is mounted on top of the machine, as indicated at 4, preferably so that a por-

tion thereof lies in front of a vertical plane containing the points of contact between the rear wheels and the floor.

The present invention is based on the fact that a curved spring bar or the like, supported at its ends, presses downwardly at both ends when an attempt is made to flatten the same. In utilizing this principle, I provide the machine with a curved handle so disposed that when the machine tends to move ahead while the operator is holding back on the rear end of the handle, forces are applied that tend to straighten the handle and thus produce a downward pressure on the front end of the machine, as well as a downward pressure on the rear end of the handle. Consequently all that the operator has to do is to pull or hold back on the handle and keep the rear end from dropping down.

The handle must not be too resilient, since otherwise the machine will chatter. I have found that when the handle is made from a metal pipe, preferably of iron or steel, and given the proper curvature, it will possess the necessary resiliency, without leaving the machine so far out of control that it will tend to move irregularly or chatter. The handle is preferably shaped as shown in the drawing, 5 representing the handle, like an inverted flattened U, the free end of the forward arm being bent forward and collapsed, as indicated at 6, so as to lie flat upon the top of the motor; the handle being fastened to the motor by bolts 7 passing through the flattened or collapsed end. On the free end of the rear arm of the handle is a cross piece 8 or handhold. It will therefore be seen that the handhold lies considerably below the highest point of the handle, permitting it to be located at such a height from the floor as to be most convenient for the operator.

Normally, when the machine is at rest, the handle is in the shape shown in the drawing. When the machine is in operation it moves ahead under its own power and the operator simply pulls back on the handholds, thereby checking or completely stopping the forward motion. The handle is therefore subjected to pulling forces acting in opposite directions at the ends thereof, and consequently the handle is straightened more or less and, in straightening exerts a downward pressure on the machine. As heretofore stated, if the handle were too

resilient, it would not hold the machine to its work but would permit the machine to chatter.

While I have illustrated and described with particularity only a single preferred form of my invention, I do not desire to be limited to the exact structural details thus illustrated and described; but intend to cover all forms and arrangement which come 10 within the definitions of my invention constituting the appended claims.

I claim:

1. The combination with a floor-surfacing machine having a surfacing roller at the 15 front end acting as a support and also as a traction member tending to move the machine ahead, of a handle extending rearwardly from said machine, said handle having a bowed spring section so positioned 20 therein that a pull on the handle tending to straighten the spring section produces a downward pressure on the roller.

2. The combination with a floor-surfacing machine having a surfacing roller at the 25 front end acting as a support for that end, and a supporting element at the rear end, of a bowed resilient handle extending upwardly and rearwardly from a point on the machine such that a downward pressure at

that point produces a downward pressure on 30 said roller, the concave side of the handle facing downwardly.

3. The combination with a floor-surfacing machine having a surfacing roller at the front end acting as a support and also as 35 a traction element tending to drive the machine ahead, and a supporting element for the rear end of the machine, of a bowed handle made of a pipe of resilient metal extending upwardly and rearwardly from a 40 point above the machine, the concave side of the handle being directed downwardly.

4. The combination with a floor-surfacing machine having a surfacing roller at the front end serving as a support for that end, 45 a supporting element for the rear end, and an operating motor mounted thereon in a position such that the front part of the casing lies in front of said supporting element, of a handle extending rearwardly from the 50 machine above the same, said handle being in the form of a forwardly and downwardly bowed spring section attached at its front, lower end to the motor casing.

In testimony whereof, I sign this specification. 55

RICHARD E. LEWIS.
